AUTOMATIC RADIO CONTROL

Emile Brugger, Valley Stream, N. Y.

Application January 29, 1936, Serial No. 61,295

13 Claims.

(Cl. 250—20)

This invention relates to radio receiving sets having mechanism to automatically select any one of a plurality of stations for radio reception at predetermined times.

5 The object of the invention is to render a mechanism of this sort more convenient to use and to give a choice of smaller time intervals.

The present application is an improvement on and a continuation in part of my application, 10 Serial No. 438,292 filed March 24, 1930 for Automatic radio station selector. In said application hour intervals only can be selected and a separate device in the form of a lever is provided for each hour. With the present improvement one-quarter hour intervals, both a. m. or p. m. may be readily useable.

20 A feature of the present invention resides in the provision of controllers which I designate "determinators", these in the specific embodiment shown, taking the form of keys, jacks or plugs which may be inserted in holes in a stationary plate on the panel board of a radio set. These holes are arranged into sets, one set for a. m. and the other set for p. m.

25 In order that various time intervals may be made available, each determinator is provided with one or more elements, each element corresponding to a time unit and when a determinator is inserted in the panel board it will cause connections to be made under control of a timing element which will bring the radio set into action at a predetermined time for a particular station and continue such action for a time interval corresponding to the number of time unit elements 30 carried by the particular determinator used. Each element on each determinator is also provided with a characteristic contour appropriate to the station which the particular determinator is to select. Thus a determinator having four 35 elements, in the present embodiment, would cause the selection of a particular station and continue reception from said station for one hour. The position which a determinator occupies on the panel board determines the time when the 40 radio set becomes operative and the interval during which it remains operative and by the contour of the element or elements carried thereby selects the desired station.

45 In other words the positioning of a determinator selects a station, establishes the local operating circuit for the radio set and at the end of a definite time interval the local operating circuit is broken.

50 Another feature of the invention resides in the provision of a continuous series of time unit devices corresponding to p. m. and a series of groups of time unit devices corresponding to a. m. These devices are arranged beneath the 55 holes in the panel board and any determinator

placed in the holes cooperates with these time unit devices.

A further feature of the invention resides in the manner of spacing the holes so that a determinator may be placed in cooperation with the 5 p. m. series of time unit devices beginning at any place in the series. For instance, if it is desired to have the radio set operative for one-half hour between 1:45 and 2:15 p. m., a determinator having two elements is placed in the holes marked 10 1:45 and 2:00.

A still further feature of the invention relates to the automatic switching from a. m. to p. m. and vice versa of the control exercised by a determinator. For instance, if it were desired to 15 have the radio set operative between 11:45 a. m. and 12:15 p. m., a determinator having one element would be placed in the a. m. hole corresponding to 11:45 and a similar one in the 12:00 hole of the p. m. series. At 12 noon, the circuits 20 controlled by the a. m. determinator would automatically be switched to the p. m. determinator.

Other features and advantages will be apparent from the following description and claims 25 taken in connection with the accompanying drawings in which:

Figure 1 is a diagrammatic representation of a panel board of a radio set having my invention applied thereto.

Figure 2 is a section considerably enlarged on the line 2—2 of Figure 1.

Figure 3 is an enlarged front view of a portion of the panel board with parts broken away.

Figure 4 is a section on the line 4—4 of Figure 3.

Figure 5 is a section on the line 5—5 of Figure 3.

Figure 6 is a detailed elevation of one of the determinators used to select station WOR, for example, and to continue the reception from said station for one hour.

Figure 7 is a similar view for three-quarter hour reception from another station designated for convenience, WJZ.

Figure 8 is a similar view of a determinator for one-half hour reception from a third station designated WEAF.

Figure 9 is a similar view showing a determinator having a single element for fifteen minutes' 50 radio reception from the same station as shown in Figure 8.

Figure 10 is a more or less diagrammatic view showing the electrical connections.

Referring to the drawings in detail 1 indicates 55 the panel board of a radio receiving set. Just inside this panel board is shown one element, 2 of a tuning mechanism which in the present drawings is illustrated as a condenser. The set may have a number of these and if so they may be con- 60

nected as usual by means of a pulley shown at 4 and belt 6. Three of these condensers are diagrammatically indicated in Figure 1, but in the following description and in the claims this 5 mechanism, whether consisting of several connected condensers, a single condenser, or other means to determine a station, will be referred to as "tuning mechanism". As shown the movable member of this mechanism is mounted on a shaft 10 7 and the usual dial 8 may be provided for setting the same by hand.

An electric motor 10 (Figure 2) is provided with a shaft 12 carrying a worm 14 engaging a worm wheel 16 carried by a shaft 17, supported 15 at one end by an upstanding bracket 18 and at the other end by bearing 20. A friction clutch 19 enables the motor to drive the shaft 7 but permits hand setting if desired. The motor is reversible, adapting it for use where the condenser 20 is limited to an arc of about 180°. The positioning of the condenser by the motor may be the same as in my application above referred to and includes a contact ring 22 mounted on the shaft 7 but insulated therefrom by a ring of non-con- 25 ducting material indicated at 24 (Figures 3 and 10). An arcuate frame 26 rises from the base of the radio set, the upper portion having an arcuate dove-tailed groove 28 for the support of station contacts 30, each carrying a brush 32 bearing 30 on the contact ring 22. To a pin on each brush is attached a lead wire. Screws 34 enable each station contact 30 to be adjusted along the arcuate slot 28. One of these station contacts is provided for each station and three are shown in 35 the present embodiment. To permit the insertion of the contacts the lower portion of the groove 28 is cut away slightly at 36. Also supported on the frame 36 is a permanent contact 38 having a spring pressed contact member 40 which also bears against the contact ring 22. The 40 electric leads from the brushes 32 are indicated at 42, 44 and 46 respectively and from the brush 40 is a lead 48.

It is to be understood that the invention in its 45 broader aspects is not dependent on how the tuning is brought about and therefore the showing of a movable condenser and a motor is to be considered merely as a conventional way of bringing about the tuning. For instance, each 50 station contact 30 might be connected to a fixed condenser set to tune to a particular station. The invention would be as applicable to such a construction as to one in which the condenser is movable. Therefore, in the claims the term 55 "tuning mechanism" is to be understood as applying to any mechanism by which a radio reception from a particular station is made available.

Referring now to Figure 2, there is provided at 60 the left hand portion thereof, a constant speed motor diagrammatically shown at 50. On the shaft of this motor, which makes one rotation in fifteen minutes, is one member of a friction clutch 52 cooperating with a similar clutch member 53 on a shaft 54 properly supported in the 65 casing and having on its end a knob 55 by which the shaft 54 may be turned independently of the constant speed motor due to the friction clutch. The shaft 54 carries an arm 55 which enables the teeth of a star wheel 56 and moves said 70 wheel one tooth at every rotation of the shaft 54, that is to say, one tooth every fifteen minutes. The star wheel carries a hub 57 by which it is secured to a shaft 58, the latter supported at one end in a bearing 59 and at its other end in a fixed 75 plate 60, suitably secured to the panel board 1, as

clearly shown in Figure 4. The panel board is cut away at 61 and the plate 60 is provided with two circular series of holes, Figure 3, into which the determinators, already referred to, are placed.

Secured to the shaft 58 below the star wheel 56 5 as shown in Figure 2, is a contact disc 62 having about its periphery an electrically conducting ring 63, Figure 4. Referring now to Figure 10, an electric plug 64 is shown in the lower right hand portion which may be connected to any suitable 10 source of electrical energy. From this plug a wire 65 leads to a binding screw 66, the other end of which is provided with a spring pressed plunger 67 which makes sliding contact with the ring 63.

Arranged about the periphery of the contact 15 disc 62 are two series of rings, the inner series consisting of the rings 68, 70, and 72, and the outer series of the rings 74, 76, and 78. These rings are of electrically conducting material but are separated from each other and from the plate 20 60, by insulating rings 80. These rings 68 to 78 constitute the station selecting mechanism and there are as many rings as there are stations to be selected. The inner series of rings enable the determinators to select stations during the p. m. 25 period, while the outer set of rings correspond to the a. m. period. All of the rings are secured together and to the plate 60.

Each set of rings is provided with a series of 30 perforations, the perforations of the inner series being continuous and registering with a similar series of perforations 82 in the plate 60. The perforations of the outer set are arranged in groups of four and register with perforations 84 35 similarly arranged in groups of four, in the plate 60. Between the plate 60 and the adjacent insulating ring 80, Figure 4, are a series of time unit 40 devices 86. These are also clearly shown in front elevation in Figure 3. Each of these time unit devices has two holes registering with the perforations 84 and 82 respectively in the rings and plate 60. There are as many of these time unit devices 45 as there are time unit intervals. In the present embodiment since the time unit interval chosen is one-quarter of an hour, forty-eight time unit devices are provided.

For convenience in description the rings 68 and 74 constituting the selecting mechanism, are shown as appropriated to station WOR. The next ring is appropriated to the station WEAF 50 and the top ring as indicated in Figure 4 or the bottom ring as indicated in Figure 3, is appropriated to the station WJZ.

Reference has been made to the lead 65 connected to the source of electrical supply. From 55 this lead the current may flow to the contact ring 63 and thence through a wire 88 to a binding post 90 connected to a spring pressed contact pin 91, said pin making contact with one or another 60 of said time unit devices, as the disc 62 is advanced step by step by the star wheel 56 through the medium of the arm 55 connected to the timing mechanism.

If it is desired to select a station, for instance, 65 WOR a determinator bearing the WOR designation is placed in holes of the plate 60. The determinator for WOR is shown in detail in Figure 6 and consists of a handle portion 92 and four time unit elements 93. This determinator will permit 70 radio reception for one hour. Each of the elements 93 as shown in Figure 6 has a lower reduced portion and an upper enlarged portion 94. Since 75 the function of a determinator is to bridge contact between one or more of the time unit devices 75

86 and a station selecting ring, the portion 94 in Figure 6 is of sufficient length to do this. The determinator for WJZ has its time unit elements differently formed, each element containing two enlarged portions, one situated immediately adjacent the handle 92 to contact with a time unit device, and the other at the end of the element 93 to contact with either of the third rings 72 or 78. For WEAF each determinator element has an enlarged portion 94 adjacent the handle and a second enlarged portion 94 situated a short distance from the end of the element 93, the latter making contact with either of the second rings 70 or 76.

15 The enlarged portion 94 adjacent the handle portion 92 is characteristic of all of the determinators and the elements are all electrically conducting. The diameter of the enlargement 94 is such as to make contact with any of the rings 68 to 78 depending upon the position of the determinators and its station characteristics. In order that a good contact may be made, each element 93 is made as a split cylinder with its upper portion secured in the handle portion 92.

25 At the left hand portion of Figure 4 a determinator having a single element 93 is shown inserted in the plate 60 and it will be noticed that the portion 94 thereof serves to bridge the time unit device 86 shown in Figures 3 and 4 corresponding to 2:45 a. m., and the ring 74 appropriated to the station WOR. As long as the contact pin 91 carried by the contact disc 62 bears upon the 2:45 time unit device, a circuit will be established to the lead 42 and contact device 30 of that station. When the star wheel 56 moves from 2:45 to 3:00 o'clock, the contact 91 passes to the next adjacent time unit device, but since there is no connection between this device and any station selecting ring the circuit to the radio set will 35 be broken. Therefore it will be seen that each determinator causes a particular station to be received for an interval depending upon the number of the elements 93 carried thereby. It will also be apparent that the contour of each element 40 determines the station to be selected.

It will be noted by reference to Figure 3 that the inner or p. m. series of holes in the plate 60 are continuous and equally spaced from each other and are arranged in a circular arc, therefore 50 any determinator having two or more elements 93 may be placed in any pair of holes. The outer series of holes corresponding to a. m., however, are arranged in groups of four, but the arc passing through the center of said group of holes is 55 struck from the same radius as the adjacent group of holes corresponding to p. m. This enables a determinator having four elements 93, for instance, to be placed in any group of a. m. holes or in any four adjacent p. m. holes.

60 The contact disc 62 is provided on its face with a series of fifteen minute time intervals running through twelve hours which are visible through a sight opening 96 provided in the plate 60 as shown in Figure 3. This is for the purpose of setting and its manner of use will be later described.

Referring now to Figure 4 and assuming that a WOR determinator has been positioned as shown, the current then passes from the plug 64, Figure 10, to the lead 65 and through the contacting ring 63 to the pin 91, thence through the time unit device 86 in contact with said pin to the enlargement 94 which connects 86 with ring 74. From the ring 74 the current passes through the wire 97 to contact 98 thence through lever 99 and wire

100 to lead 42 connected to the station contact 30 corresponding to WOR.

In the particular embodiment of the invention shown, the current then passes through the conducting ring 22 to contact 48, wire 101, to the motor 10; thence by way of wires 102 to pole piece 103 through wire 104 to the armature 105 of the motor and through wire 106 to pole piece 107, thence through wire 108 to the other side of the line at 109. The motor is energized and rotates 10 the ring 22 in the direction of the arrow, Figure 10, until a non-conducting inset 111 on the ring 22 comes into register with the contact piece 42. The circuit is then broken through the motor, but another circuit is established through the pole 15 piece 42 to the conducting portion 112 of the inset and the current then passes through wire 113 to the radio set making it operative. From the radio set it passes to the other side of the line through wire 114.

If the determinator were of the contour shown in Figure 9, the current after passing through the conducting ring 63, pin 91 and unit device 86 corresponding to a particular time, would pass through the determinator and to the second station selecting ring 75 and by way of wire 115 to contact 116, thence through conducting lever 117 to wire 118, to pole piece 44 corresponding to station WEAF. The motor would again start in the direction of the arrow shown in Figure 10 but 30 when the inset 111 reached the position shown in Figure 3, the motor would be reversed by any well known reversing mechanism, such for instance, as that described in my pending application above referred to, and would move in the opposite direction until the inset 111 coincided with the pole piece 32 of the contact piece 30 corresponding to WEAF thereby breaking the current through the motor and establishing the local operating circuit through the set.

40 If a determinator, such as shown in Figure 7 corresponding to WJZ, were placed in any group of the a. m. holes, the current would pass from the ring 78 through wire 120 to contact 121, thence through lever 122 to wire 123 to pole piece 46 45 corresponding to WJZ on the conducting ring 22.

It will thus be seen that any determinator, depending upon the contour of its elements 93 will select the station appropriate to the particular determinator and said station will be received 50 for as many unit intervals of time as there are elements 93 on the particular determinator used.

It has been stated that the plate 60 is provided with perforations corresponding to both p. m. and a. m. designations. Therefore, in order that 55 the proper station may be selected by a determinator, means are provided whereby the control which such determinator exercises is automatically switched from a. m. to p. m. or from p. m. to a. m. at the position of the star wheel 60 56 corresponding to 12:00 o'clock whether this be 12:00 noon or 12:00 midnight.

65 This switching is effected through mechanism more or less diagrammatically indicated in Figure 10 and includes an arm 124 carried by the 65 shaft 58 to which the star wheel 56 is secured. When the star wheel moves to 12:00 as indicated by the pointer 126, Figure 3, the arm 124 moves from the position shown in Figure 10 to the dotted line position shown in Figure 3 and in so 70 doing a finger 127 on said arm engages one of four pins 128 carried by a star wheel 129 supported on a shaft 130 on the panel board of the radio set. The star wheel has four points with a depression therebetween, which depression is 75

engaged by a spring pressed ball 131 and normally holds the star wheel at whatever position it has been moved by the arm 124. The star wheel carries an electrically conducting arm 132 which in Figure 10, is shown as engaging a pole piece 133 connected by a wire 134 to a switch 135, which switch, as shown in Figure 10 is engaged by a core 136 of a solenoid 137 suitably supported in a frame member 138. The core 136 is shown as having moved the switch member 135 to position it away from contact 140 so that no current flows through the solenoid 142 which when actuated serves to break the circuit between 135 and 140. When the arm 124 moves to the position shown in Figure 3 the star wheel is moved through 90° partly by the arm 124 and partly by the spring pressed ball so that contact 132 makes engagement with pole piece 144. A circuit is then established from the plug 64 through wires 65 and 146, to wire 147 thence to solenoid 137 returning by wire 148 and through spring contact 150 to wire 151 to pole piece 144, contact arm 132, to wire 152 to the other side of the line. Solenoid 137 having thus been energized, its core 136 will be moved to the left as shown in Figure 10 and carry with it the floating piece 154 to which the levers 99, 117, and 122 are pivoted, said levers being fulcrumed in the frame 138 at the points 155, 156 and 157. The floating piece 154 also engages the core 158 of the solenoid 142 and moves it from the position shown in Figure 10 to a position such that said core engages the spring contact 150 and moves it to position to break contact between it and the wire 148 thereby breaking the circuit through the solenoid 137, spring contact 150 being then in the same relative position as shown at the right between the spring contact 135 and the wire 140. A snap spring 160 holds the floating piece 152 and the levers 99, 117 and 122 in either position to which they are moved by the cores of the solenoids.

When the star wheel 56 has made another rotation and the arm 124 is again ready to move the star wheel 129, the arm 132 will be moved from the pole piece 144 to the pole piece 163 and current will be then established from the plug 64 through wire 152, arm 132 to pole piece 163 to wire 170, and wire 134, to contact 135, wire 140 to solenoid 142, through said solenoid to wire 148. Solenoid 142 will then be actuated to move the floating piece 154 back to the position shown in Figure 10 and in so doing will break the contact between 135 and 140 and the part will again be positioned for a. m. selections. In other words the pole pieces 133 and 168 correspond to a. m. and the pole pieces 144 and 172 correspond to p. m.

In order that the user of the radio set may determine at a glance whether the switching mechanism is in a. m. or in p. m. position, the shaft 130 extends through the panel board and on the outside thereof a pointer 174 is provided and the designations a. m. and p. m. appear on the outside of the panel board. The pointer 174 may be moved by hand in either direction to properly set the solenoid cores corresponding to the time of day.

Since the arm 54 makes but one rotation in fifteen minutes, the arc of its movement while in contact with the star wheel, is relatively slow and in order that the pin 91, Figure 4, carried by the contact disc 62 may quickly move from one time unit device 86 to another, a spring pressed pawl 176 is provided and the timing is such that

the pin 91 remains in contact with one of the time unit devices 86 until the point of the star wheel has passed the point of the pawl 176 when the pawl spring acts to quickly move the star wheel and quickly jump the pin 91 from one device 86 to the next. 5

It will be noted that as soon as the star wheel has moved to a position where a unit device 86 and a station selecting ring is not bridged by the enlarged portion 94 of an element 93 of a determinator, the circuit through the radio set is broken and reception from the particular station controlled by said determinator ceases. 10

It is apparent that a number of determinators corresponding to a particular station may be provided. For instance, for WOR in addition to a determinator such as is shown in Figure 6, other determinators having three, two and one element 93 would be provided, each element however, having a contour characteristic of the station to 15 be selected thereby. It is obvious of course that several sets of determinators for the same station may likewise be provided in order to permit the same station to be received at different times with but one adjustment of the determinators. It is 20 also obvious, however, that a single set of determinators for each station will be sufficient, but if the same station is to be repeatedly received, the determinators will of course have to be re-positioned. 25

By having a sufficient number of determinators it is possible to set these so that any station may be received at fifteen minute intervals or any multiple thereof throughout the entire twenty-four hours, and after having been once positioned, the stations will be received in the order that the determinators are set without any further attention whatever on the part of the user of the radio set. The radio will be silent during all intervals where no determinator is in operative 40 position, but the set will become automatically operative when any determinator begins to exercise its control in cooperation with the timing element. 30

At 12:00 noon, the control which has previously been exercised by one or more determinators which have been placed in the a. m. holes will automatically be switched to control by determinators which may have been placed in p. m. holes all without any attention on the part of the user except the initial positioning of the determinators. 45

What I claim is:

1. In a radio receiving set, the combination with tuning mechanism, a motor for moving said mechanism through an arc of radio reception corresponding to a plurality of stations; of station selecting and time unit devices, a plurality of determinators each having time unit elements, each element having a contour appropriate to a station and means cooperating with each determinator whereby an element of a determinator by its contour controls the movement of said tuning mechanism by said motor and by the number of its time unit elements determines the time interval during which the particular station selected shall be received. 55

2. In a radio receiving set, the combination with tuning mechanism movable through an arc of radio reception, station selecting and time unit devices, a unitary determinator having a plurality of time unit elements carried thereby each element having a contour appropriate to a station, and means cooperating with the said determinator whereby an element thereof by its con- 75

tour controls the degree of movement of said tuning mechanism to select a station and by the number of its time unit elements determines the time interval during which the selected station shall be received.

3. In a radio set, the combination with tuning mechanism, a motor for moving said mechanism through an arc of radio reception corresponding to a plurality of stations; of station selecting means, time unit devices, a plurality of determinators each having means to cooperate with the same station selecting means to determine the movement of said motor to select a particular station and to cooperate with a different number of said time unit devices to determine different time intervals during which the selected station shall be received.

4. In a radio set, the combination with tuning mechanism, a motor for moving said mechanism through an arc of radio reception corresponding to a plurality of stations; of station selecting means, a series of time unit devices, a determinator having elements carried thereby for cooperating with said station selecting means and with a plurality of successive time unit devices at any point in the series thereof, and means brought into action by the cooperation of said elements of said determinator with said time unit devices to control the interval during which the selected station shall be received.

5. In a radio set, the combination with tuning mechanism, a motor for moving said mechanism through an arc of radio reception corresponding to a plurality of stations; of station selecting means including a continuous series of time unit devices corresponding to p. m. and a series of groups of time unit devices corresponding to a. m., a determinator having time unit elements carried thereby for cooperation with successive time unit devices of said p. m. series and with any group of a. m. devices, said time unit elements of said determinator also cooperating with said station selecting means, and means brought into action by the cooperation of said elements of said determinator with said time unit devices to control the interval during which the selected station shall be received.

6. In a radio set, the combination with tuning mechanism, a motor for moving said mechanism through an arc of radio reception corresponding to a plurality of stations; of means for controlling the amount of movement of the tuning mechanism by the motor and having electrical connections with said motor, station selecting means including a series of time unit devices corresponding to p. m., a series of time unit devices corresponding to a. m., a source of current, a timing element for successively connecting said time unit devices with said current source, a determinator adapted to cooperate with a time unit device of either the a. m. or p. m. series, means carried by said determinator for completing the circuit through a time unit device to the motor when cooperating with any one of said a. m. or p. m. time unit devices, under control of said timing element, and means for automatically switching the circuit control exercised by said determinator from the a. m. to p. m. series of time unit devices or vice versa when said timing element passes a given position.

7. In a radio receiving set, the combination with tuning mechanism; of station selecting means, time unit devices, a determinator for cooperating with a station selecting means to de-

termine the tuning in of a station and for simultaneously cooperating with a definite plurality of said time unit devices to determine how long the particular station shall be received.

8. In a radio set, the combination with tuning mechanism; of station selecting means, time unit devices, a plurality of determinators each having means to cooperate with the same station selecting means to determine tuning in of a particular station and to cooperate with a different number of said time unit devices to determine different time intervals during which the selected station shall be received.

9. In a radio receiving set, the combination with tuning mechanism; of station selecting means including a continuous series of time unit devices corresponding to p. m., a series of groups of time unit devices corresponding to a. m., a determinator having elements cooperating with successive time unit devices of said p. m. series and any group of a. m. devices, said determinator also having means to cooperate with said station selecting means, and means brought into action by the cooperation of said elements of said determinator with said time unit devices to control the interval during which the selected station shall be received.

10. In a radio receiving set, the combination with tuning mechanism; of station selecting means including a series of time unit devices corresponding to p. m., a series of time unit devices corresponding to a. m., a source of current, a timing element for successively connecting said time unit devices with said current source, a determinator adapted to cooperate with said time unit devices of either the a. m. or p. m. series, means carried by said determinator for completing the circuit through a time unit device to the tuning mechanism under control of said timing element, and means for automatically switching the current control exercised by said determinator from the a. m. to the p. m. series of time unit devices or vice versa when said timing element passes a given position.

11. In a radio receiving set, the combination with tuning mechanism; of station selecting and time unit devices, a plurality of determinators having time unit elements, each element having a contour appropriate to a station, and means cooperating with each determinator whereby each element thereof by its contour controls the tuning in of a station and by the number of elements carried thereby determines the time interval during which the particular station selected shall be received.

12. In a radio set, the combination with tuning mechanism; station selecting means including a plurality of electrically conducting members one for each station, time unit devices, a plurality of determinators each having means to electrically connect a station selecting means with one or more time unit devices, different determinators having different numbers of elements for cooperating with different numbers of time unit devices.

13. In a device of the character described, in combination, circuit selecting means, time unit devices, a plurality of determinators each having means to cooperate with the same circuit selecting means to determine the closing of the selected circuit and simultaneously to cooperate with a different number of said time unit devices to determine different time intervals during which the selected circuit shall remain closed.

EMILE BRUGGER.
